UNITED STATES PATENT OFFICE.

CHRISTIAN J. LETZING, OF BOSTON, MASSACHUSETTS.

LOCK.

SPECIFICATION forming part of Letters Patent No. 341,025, dated May 4, 1886.

Application filed July 27, 1885. Serial No. 172,713. (No model.)

To all whom it may concern:

Be it known that I, CHRISTIAN J. LETZING, of Boston, in the county of Suffolk and Commonwealth of Massachusetts, a citizen of the 5 United States, have invented a new and useful Improvement in Door-Locks, of which the following is a full, clear, and exact description, reference being had to the accompanying drawings, forming a part of this specification, in 10 explaining its nature.

The object of the invention is to provide means whereby a door upon being unlocked may be opened but a limited distance, and also in various details of construction, all of 15 which will be hereinafter fully described.

Referring to the drawings, Figure 1 is a perspective view representing the application of a lock containing the features of my invention to a door. Fig. 2 is a view in horizontal section, representing the door closed in dotted lines and open in full outline. Fig. 3 is an enlarged view in elevation of the lock, looking from behind, to show its interior construction, and also to represent the parts when the latch-bolt is in its protracted position. Fig. 4 is a 20 view in elevation of the same parts when the latch-bolt is in its normal position. Fig. 5 is a detail view, and Fig. 6 is a modification hereinafter referred to.

30 A represents a door provided with a lock having the features of my invention.

B represents the frame-work about the door.

C is the lock. It has a latch-bolt, c, which is provided with the inclined edge or face c', 35 the long slot c², and the passage or entrance c³ to the slot, which extends from the end of the slot. This latch-bolt is movable in relation to the casing of the lock, as hereinafter specified, and it is adapted to engage with the catch D, 40 which projects outwardly from the inner surface of the frame of the door. This catch consists of the part d, having screw-holes d', by which the catch is fastened in place, and the comparatively thin outward-extending plate d², having the shoulders d³, Fig. 5. This plate d² is somewhat less in thickness than the width of the passage or entrance c³ to the slot of the latch-bolt, and when the door is closed said latch-bolt is adapted to project upon this plate, 45 the portions c' bearing against the shoulders d³, as represented in Fig. 5. These shoulders

are formed by the ear d⁴ and the end d⁵ of the swinging bar E, which is fastened to the said ear. There is arranged at the end of this swinging bar a cross-block, e, which acts as a 55 stop for the latch-bolt and door, as hereinafter described.

For ordinary use the latch-bolt c is moved inward into the lock-casing to disengage it from the catch. If, however, it is desired to 60 limit the movement of the door so that it may be opened a limited extent, and then locked, I move the latch-bolt outward beyond the plate d², so that the slot c² comes beneath the shoulders d³ of the latch, and, the slot being wider 65 than the shoulders, I am then enabled to open the door, the latch-bolt passing by the shoulders onto the bar E, which is of a greater width than the width of the entrance or passage c³ to the slot, so that the latch as the door 70 is moved outward rides on the swinging bar until it comes in contact with the stop e. This construction effectually prevents the door from being opened a greater distance than is desired, the distance being regulated by the 75 length of the swinging bar.

In closing the door it may be shut in the ordinary manner, or the bar E may be used as a lever in returning the latch-bolt to a position within the line of the shoulders d³, and 80 it will automatically return to its normal position.

There are many ways, of course, by which this latch-bolt may be provided with the necessary movements, and in the drawings I have 85 illustrated one of these ways only. The latch-bolt c has a shank, c⁵, extending backward, and provided with a slot, c⁶, which receives the guides or blocks c⁷, projecting outward from the casing of the lock, to act as 90 guides in connection with the slot. The shank also has two pins, c⁸, projecting outward therefrom, and they are engaged by the arm f, extending outward from the barrel f', turned by the door-handle f². A spring, f³, serves to 95 automatically return the barrel. A spring, f⁴, bears against the shoulder f⁵ upon the latch-bolt, and holds it in its normal position. The lock also has the tumblers f⁶, which are adapted to engage the tongue f⁷ upon the end of the lever f⁸, which is pivoted at f⁹, and the end of which projects into the recess f¹⁰, cut in the 100

shank c^5 . The latch-bolt also has a notch, g , in its shank, for the reception of the push-block g' , whereby the latch is held locked, and which block also acts to lock the latch when it is pushed forward, so that it cannot be unlocked by the key. This block is adapted to be moved upward by the lever g^2 and push-block g^3 , pivoted thereto, the lever being pivoted at g^4 . A spring surrounds the pivot-post and bears 10 against the lever, to exert sufficient friction thereon to maintain the block in any position in which it may be moved.

In Fig. 6 I represent the latch-bolt with a closed slot, instead of an open one, and use 15 in connection therewith a modified form of locking-bar. The locking-bar in this case being in the form of a hook, the end is adapted to act as an abutment, against which the latch-bolt shall come in contact when it is used in 20 the ordinary way; but when said latch-bolt is moved outward sufficiently to bring the slot in line with this portion of the hook it may then ride outward thereon, as upon the portion shown in Fig. 1. Of course this hook is 25 pivoted to swing laterally.

The advantages of the invention arise from the simplicity of the construction, and from the fact that the movement of the latch-bolt only is required to bring the controlling-bar 30 into effect.

Having thus fully described my invention, I claim and desire to secure by Letters Patent—

1. In a lock, the combination of a bolt or latch shaped as described, and adapted to be

35 moved by a spring to engage with a catch, and to be moved by the knob or handle outwardly, to be disengaged from the catch, and to engage with the locking-bar, with the locking-bar E , and the plate d , having the shoulders d^3 , all substantially as and for the purposes 40 described.

2. The combination, in a lock, of the bolt or latch shaped substantially as described, and adapted to be moved by a spring to engage with a catch, and to be moved by the 45 knob or handle outward, to be disengaged from the catch to engage with the locking-bar, the plate d , having the shoulders d^3 , forming the catch, the swinging locking-bar E , secured to said plate, and the cross piece, block, or 50 stop e , for limiting the extent of movement of the bolt or latch, all substantially as and for the purposes described.

3. The combination of the latch-bolt c , shaped substantially as specified, to act as a 55 latch and as a locking device, the operating-arm f , spring f^4 , and the guides c' , and the latch knob or handle, whereby the latch-bolt is adapted to automatically engage the catch, and to be moved by hand both outward and 60 inward from the position to which it is automatically moved, all substantially as and for the purposes described.

CHRISTIAN J. LETZING.
